DESIGN FOR A HUMIDIFIER OR THE LIKE

Hans Rudolf Stoop, Zug, Switzerland, assignor to Defensor
A.G., Zurich, Switzerland, a Swiss corporation

Filed Jan. 3, 1969, Ser. No. 15,204

Claims priority, application Switzerland Sept. 4, 1968

Term of patent 14 years

Int. Cl. D23—04

U.S. Cl. D23—147

FIG.1

FIG.2

FIG.3

FIG. 4

FIG. 5

FIG. 6

FIG. 7

FIG. 1 is a perspective view of the humidifier embodying my new design;

FIG. 2 is a side view thereof;

FIG. 3 is a top view thereof;

FIG. 4 is a front view thereof;

FIG. 5 is a bottom plan view thereof;

FIG. 6 is a rear view thereof; and

FIG. 7 is a fragmentary view of the perforated covering panel for the top, sides and bottom of the humidifier.

The undisclosed remaining side of the atomizer is substantially identical to the side shown in FIG. 2.

I claim:

The ornamental design for a humidifier or the like, substantially as shown and described.
